UNITED STATES PATENT OFFICE.

WEBSTER FELS KELLER, OF CINCINNATI, OHIO.

CLOTH-MARKER.

No. 893,518.

Specification of Letters Patent.

Patented July 14, 1908.

Application filed September 26, 1907. Serial No. 394,731.

To all whom it may concern:

Be it known that I, WEBSTER F. KELLER, a citizen of the United States, residing in Cincinnati, in the county of Hamilton and State 5 of Ohio, have invented a new and useful Improvement in Cloth-Markers, of which the following is a specification.

This invention is a new and useful construction of cloth marker, the object being to 10 provide an exceedingly cheap, simple and efficient form of device by means of which cloth can be marked in a regular manner, said device being particularly intended for use where it is desired to cut cloth into strips 15 and in which the marking of the cloth is a necessary preliminary operation.

Another object of the invention is to provide a marking device which can be quickly and easily adjusted so as to measure off a 20 mark any desired width.

With these various objects in view, my invention consists broadly in the employment of a strip provided with wheels or rollers at each end, said strip having an adjustable 25 chalk holding device connected thereto.

The invention consists also in the employment of a graduated strip and also of the novel construction of chalk-holding device.

The invention consists also in certain de- 30 tails of construction, hereinafter fully described and pointed out in the claims.

In the drawing forming a part of this specification:—Figure 1 is an end view of a cloth marker constructed in accordance with my 35 invention. Fig. 2 is a top plan view of the same. Fig. 3 is a detail sectional view showing the manner of connecting chalk holding device to the graduated strip, and Fig. 4 is a detail view of the chalk-holder.

40 In carrying out my invention I employ a graduated strip A which is preferably graduated in inches and fractions thereof and this strip may be any length desired, and also of any suitable material. A wheel or roller B is mounted at each end of the strip A, and a handle C is connected to this strip for the purpose of easily pushing the marker along the cloth. The strip A is grooved longitudinally adjacent its front edge upon its top and bottom faces as shown at A', said grooves being adapted to receive the rib portions D'

formed upon the wings of the spring clasp D, and this spring clasp D is connected with another spring clasp E, somewhat larger than the clasp D and having its wings formed with 55 barbs E' in order to securely hold a piece of tailor's chalk F between the wings or jaws of the clasp E. This clasp E is arranged vertically as shown whereas the clasp D is arranged horizontally, and in practice I prefer 60 to construct this compound clasp with one common member, but it will of course be understood that any other equivalent construction may be employed.

The strip A is graduated and the top mem- 65 ber of the clasp D is formed with a projecting pointer-finger D² which will clearly indicate the relative position of the chalk with reference to the ends of the strip.

In operation the chalk-holder is adjusted 70 at the desired point and in the drawing I have shown this holder adjusted to mark a line two inches from the end of the strip, and the marker is then placed upon the cloth with the wheel at the end upon the extreme edge 75 of the cloth, and the device is then pushed forwardly maintaining the wheel always at the edge of the cloth, and in this manner a mark will be produced which will be parallel at all points with the edge of the cloth. In 80 case a number of marks are desired before the cloth is cut, the marker can be arranged so that the wheel will travel along the line previously made instead of along the edge of the cloth.

85 It will thus be seen that I provide a simple and efficient construction of cloth marker, capable of carrying out all the objects hereinbefore referred to.

Having thus fully described my invention, 90 what I claim as new and desire to secure by Letters Patent is:

1. A cloth marker comprising a graduated strip provided with wheels at each end, and a two-part clasp, one part being connected to 95 the graduated strip and the other part adapted to receive and hold a piece of chalk.

2. A cloth marker comprising a grooved strip having a handle connected thereto and provided with wheels at each end, a horizon- 100 tal clasp having ribs upon its members adapted to engage the grooves of the strip,

and a vertical clasp connected to the horizontal clasp having its members provided with barbs for the purpose specified.

3. A cloth marker comprising a grooved and graduated strip provided with a handle and having wheels at each end a two-part clasp, one part thereof being horizontal and having its members provided with ribs and

an indicating pointer, the other part of the clasp having its members provided with 10 barbs for the purpose of holding a piece of chalk, as set forth.
